UNITED STATES PATENT OFFICE.

ARTHUR S. JOHNSON, OF HOPEDALE, MASSACHUSETTS, ASSIGNOR TO DRAPER CORPORATION, OF HOPEDALE, MASSACHUSETTS, A CORPORATION OF MAINE.

LOOM STOP MECHANISM.

Application filed July 28, 1925. Serial No. 46,564.

To all whom it may concern:

Be it known that I, ARTHUR S. JOHNSON, a citizen of the United States, and a resident of Hopedale, in the county of Worcester and State of Massachusetts, have invented an Improvement in Loom Stop Mechanisms, of which the following description, in connection with the accompanying drawings, is a specification, like characters on the drawings representing like parts.

This invention relates to looms and more particularly to means for stopping the loom on the occurrence of a warp or weft fault.

It is now the common practice to equip looms with means for stopping the loom when a warp thread breaks or becomes too slack for weaving purposes, and also to stop the loom when the weft or filling fails to be laid in the shed. Such mechanisms, however, have introduced complications in the loom structure, and one of the objects of the present invention is to provide means for stopping the loom on the occurrence of a warp or weft fault, which mechanism shall be simple in construction and effective upon the occurrence of either fault to promptly bring the loom to rest.

In weaving certain fabrics, particularly of fine character, such as worsteds and the like, it is usual to employ a center fork weft stop mechanism, the weft fork of which mechanism is adapted to feel for the filling laid in the shed, and on its absence effect loom stoppage as the lay moves to its front position. In such type of weft stop mechanism, where a warp stop mechanism is also employed, an occurrence of a fault in the warp has occasioned the stopping of the loom on a backward movement of the lay.

In the use of a warp stop mechanism associated with a center fork weft stop mechanism, should the former act to stop the loom on the backward movement of the lay, the shuttle will be picked when the lay is in its backward position, and is liable to strike the center fork, thereby either causing breakage or forcing the shuttle through the warp threads.

In accordance with the present invention, the loom is brought to rest on the occurrence of either a warp or a weft fault when the lay is moving frontward, and consequently the shuttle is in its box and not liable to

occasion the defective action herein before noted.

In carrying the invention into practical effect the warp stop mechanism and center fork weft stop mechanism act upon the same dog which is connected to the loom stopping means, so that in the event of a warp or a weft fault, the loom will be stopped as the lay is moving towards front position, so that the harnesses are more nearly level at such time and the warp threads are under less strain. The operative gets accustomed to having the loom stop in the same position, whether such stop is effected either by a warp or a weft fault.

The invention, new combination of parts and novel features thereof, will best be made clear from the following description and the accompanying drawings of one good form thereof.

In the drawings:

Fig. 1 is a side elevation of sufficient portions of a loom having the present invention applied thereto, to make clear the construction and mode of operation, the relation of parts being shown as the loom is being stopped due to a warp fault;

Fig. 2 is a perspective view with parts broken away, showing on an enlarged scale the train of mechanism associated with the loom stopping means;

Fig. 3 is an enlarged detail showing more particularly the dog and dog carrier and its connection with the loom stopping means; and

Fig. 4 is a detailed perspective view of one form of warp stop mechanism that may be advantageously employed to effect loom stoppage on frontward movement of the lay.

The loom frame 1 may be of usual construction now well-known, and has mounted thereon in the usual manner the lay swords 2 carrying the lay 3 which is given its beat-up movement through a pitman 4 connected by a crank 5 to the crank shaft 6, as usual.

The center fork weft stop mechanism is shown as comprising the fork or tines 7 mounted upon a rocking head 8 pivotally mounted at 9 to lugs 10 extending from the lay 3. The inner portion of the head 8 is connected by a rod 11 to a crank arm 12 on the shaft 13 mounted in bearings 14 and 15 carried by the lay, and the lay itself has an

opening 16 into which the fork may drop when a weft thread fails to be laid in the shed. The center weft fork stop mechanism thus far described is of the usual type, or 5 may be, and secured to the outer end portion of the shaft 13, as at 17, is a dagger 18, which, as the lay goes back, rides upon the dagger rest 19, thereby lifting the weft fork 7 out of the path of the shuttle as it is 10 picked. On forward movement of the lay and when the dagger 18 moves from its supporting relation with the dagger rest 19, the weight of the dagger and connected parts causes the dagger 18 to drop and move the weft fork 7 towards the slot 16 in the lay. If, at such time, the filling has been properly laid in the shed, the weft fork will engage the filling and the dagger 18 will be 15 held in an upper position and not permitted to drop to its full throw, but should the filling 20 not be laid in the shed under the weft fork, then the weft fork will move into the slot 16 without obstruction and the dagger 18 will drop to its lowest position as the lay 25 moves forwardly and cause loom stoppage as will presently appear.

Secured to the loom frame by a bolt 20 is 30 a bracket 21 provided with a slot 22 whereby the bracket may be adjusted in position, and the upper surface 23 of the bracket affords a rest for the dagger 18 when the dagger is permitted to drop to its lowest position owing to failure or fault in the filling. Under such conditions, that is, on the occurrence 35 of a weft fault, the dagger is positioned to engage with a dog which is itself connected to the loom stopping mechanism to thereby effect loom stoppage as the lay moves forwardly and substantially reaches front position, at which time the warp threads are evened and tension thereon is 40 released.

Pivottally mounted on a bolt 23 adjustably secured to the bracket 21 by means of the 45 slot 24 is the dog carrier 25, best shown by Fig. 3, and to the upper end portion of the dog carrier is pivottally connected the dog 26. The dog 26 is mounted upon a pivot 27 on the dog carrier and has a downwardly 50 extending finger 28 normally under the influence of a light spring 29, and to maintain the dog 26 in its normal position relative to the dog carrier and dagger.

The lower end portion 30 of the dog carrier 55 is connected to the loom stopping mechanism, herein shown in the present instance of the invention as the shipper 31. This connection with the loom stopping mechanism may be variously contrived but as shown 60 consists of a link 32 having a pin and slot connection 33 with the shipper 31. The rear end portion of the link 32 is provided with a rod 34 which passes through an opening in a swivel pin 35 mounted for rotative movement in the lower end 30 of the dog carrier.

It is desirable in most instances to yieldingly connect the dog carrier with the loom stopping mechanism, and in the present instance of the invention, the rod 34 is of circular cross-section and a spring 36 is interposed between the swivel pin or block on the lower end of the dog carrier and the adjusting nut 37 on the bolt 34. Similarly, the opposite end portion of the rod 34 which extends through the swivel pin or block 35 is 70 provided with a spring 38 interposed between the adjusting nut 39 and the adjacent side of the dog carrier or swivel block, the construction being such that upon movement of the dog carrier upon its pivot in either 75 direction, a yielding action will take place between the dog carrier and the link connecting the dog carrier to the loom stopping mechanism. 80

From the construction thus far described 85 it will be apparent that upon the occurrence of a fault in the weft or filling, the dagger 18 will drop to its lower or stopping position as hereinbefore described, and on forward movement of the lay will strike the dog 26 90 which is in its normal position relative to the dog carrier and through the action of the loom stopping mechanism or shipper 31 effect loom stoppage.

It has not been deemed necessary herein to 95 illustrate the train of mechanism between the shipper and power means of the loom, such as a belt or clutch actuated by the shipper, since such train of mechanism is now well understood in the art and the details thereof form no part of the present 100 invention.

In accordance with the present invention as above outlined, the lay will be arrested 105 and the loom stopped when the lay is moving frontwardly, and in order that such stopping of the loom may take place also upon the occurrence of a warp fault, means are provided for moving the dog 26 into the normal 110 path of movement of the dagger 18 on the occurrence of a warp fault. Various types of warp stop mechanism may be employed and have associated therewith a train of mechanism for moving the dog into the path 115 of the dagger on the occurrence of a warp fault, but in the present instance of the invention the warp stop mechanism is shown as comprising the side frames or warp supports 40 which may be connected to the opposite sides of the loom as by the brackets 41. Extending between the brackets 41 of the warp stop mechanism are the drop wire guides 42 which are shown as passing through slots formed in the series of drop 120 wires 43.

Mounted for rocking movement upon the main portion of the warp stop mechanism, as by the brackets 44, is a shaft 45 having the upwardly extending arms 46 carrying the usual feeler or detector 47. Secured to 125

the rock shaft 45 is the block 48 having a cam lug 49 which is normally engaged with a cam lug 50 carried by a sleeve 51 loosely mounted on the rock shaft 45 and normally 5 pressed into operation with the cam 49 by a spring 52. Secured to the sleeve 51 is the arm 53 to which is connected a rod 54 actuated from a going part of the loom, the construction being such that upon actuation 10 of the rod 54 the rock shaft 45 will be rocked back and forth to carry the feeler or detector 47 transversely of the series of drop wires, as usual. In the present instance of the invention, the rod 54 is pivotally connected at 55 to a lever 56 pivotally mounted at 57 and normally bearing upon the cam 58 under the impulse of a spring 59, the construction being such that upon rotation of 15 the cam 58, which is shown as mounted on the under or cam shaft 60, the rock shaft 45 will be rocked during normal weaving operation.

Upon the occurrence of a warp fault, such as breakage or undue slackness, the associated drop wire 43, as indicated in Fig. 1, will drop into the path of the detector or feeler 47 and thereby arrest its rocking movement, and such arrest of the feeler or detector movement is utilized in the present invention to move the dog 26 into the path of the dagger 18 on the occurrence of a warp fault, so that the loom will be stopped as the lay moves towards and reaches front position.

35 Any suitable train of mechanism may be utilized between the warp stop mechanism and the dog 26 to effect the intended purpose, but as herein shown, a flexible sheathed wire 61 is utilized, one end of the sheathed wire 61, as indicated in Fig. 4, rests against one end of an indicator wire 61^x and the other end of which rests against a portion of the sleeve 51, with the result that should the feeler or detector 47 be arrested by a drop wire, the sleeve 51 will move longitudinally of the rock shaft 45 against the tension of the spring 52 and perforce move the flexible wire 61 longitudinally in its sheath 62, and such longitudinal movement of the sheathed wire 61 is utilized to lift the dog 26 from its normal position into the path of movement of the dagger 18 of the center fork weft stop mechanism.

55 As indicated in Fig. 3, the upper arm of the dog carrier is provided with an opening 63 in which is secured a block 64 through which extends the flexible sheathed wire, the end of which rests against a block 65 carrying a pin 66, the end of which underlies the dog 26, as indicated in Fig. 3. From the construction described, it will be apparent that should a warp fault occur, the sheathed wire 61 will be moved longitudinally in its sheath and lift the dog 26 into the path of movement of the dagger 18, so that, as the

lay moves frontwardly, the dog will be actuated and through the connection with the loom stopping mechanism, as described, effect loom stoppage as the lay moves towards front position, such condition being represented in Fig. 1. 70

When the loom is stopped, it may be that the weaver will turn back the lay without picking the shuttle, in which case either no filling will be laid in the shed or the filling is apt to get from beneath the filling fork, and if the loom were at once started under these conditions the dagger 18 would again effect loom stoppage on the first beat-up regardless of whether the stoppage has been caused by a warp or a weft fault. To prevent this, a shield 67 is connected to the bracket 21 by pins 68 which pass through diagonal slots 69 formed in the shield, so that should the shield be moved rearwardly it would be raised.

Pivots mounted at 70 on the bracket 21 is a shield actuator 71 having a tail 72 adapted to be engaged by a spring finger 73 carried by the rock shaft 74 from which extends the finger 75 adapted to be engaged and cause rocking movement of the rock shaft 74 by the shipper as it moves to loom stopping position, the effect being that when the loom is stopped by either a warp or weft fault, the shield 67 will be raised sufficiently high to support the dagger 18 in a path of movement above the dog 26, so that on starting the loom, loom stoppage will not again occur on the first beat-up of the lay. In order to return the shield 67 to its lowered position, as indicated in Fig. 2, it is provided with an abutment 76 and as the lay moves frontwardly on the first beat-up, the shield will be moved frontwardly by the dog 18 and consequently positioned in its unshielding or lowered position.

From the construction described it will be noted that the present invention provides a center fork weft stop mechanism and a warp stop mechanism, and a single dog which is adapted to be engaged in its normal position by the dagger 18 of the center fork weft stop mechanism on the occurrence of a weft fault, and that when no weft fault occurs, such single dog is moved into position to be engaged by the dagger to stop the loom on the occurrence of a warp fault, the stopping action of the loom being effected in both instances when the lay is moving frontward and substantially reaches front position. 110 115 120 125

What is claimed is:

1. In a loom, the combination of a warp stop mechanism and a center fork weft stop mechanism including a dagger, a single dog adapted to be actuated by the dagger on the occurrence of a weft fault, a dog controller connected to the warp stop mechanism to position the dog in the path of the dagger on the occurrence of a warp fault, loom 125

stopping mechanism and connections between the dog and loom stopping mechanism to effect loom stoppage on frontward movement of the lay on the occurrence of either a warp or weft fault.

5 2. In a loom, the combination of a warp stop mechanism and a center fork weft stop mechanism including a dagger, a dog normally positioned to be engaged by the

10 dagger on the occurrence of a weft fault, means actuated by the warp stop mechanism to move the dog into position to be engaged by said dagger on the occurrence of a warp fault, and means for stopping the loom when

15 the dog is actuated by the dagger as the lay moves frontward on the occurrence of either a warp or weft fault.

3. In a loom, the combination of a warp stop mechanism and a center fork weft stop

20 mechanism, loom stopping mechanism, a dog connected to the loom stopping mechanism and normally positioned to be actuated to stop the loom by the center fork weft stop mechanism on the occurrence of a weft fault,

25 means between the warp stop mechanism and the dog to move the dog into position to be actuated by the center fork weft stop mechanism on the occurrence of a warp fault.

4. In a loom, the combination of a warp stop mechanism and a center fork weft stop mechanism, loom stopping mechanism, a dog carrier connected to the loom stopping mechanism, a dog mounted on the dog carrier and normally positioned to be actuated to stop

35 the loom by the center fork weft stop mechanism on the occurrence of a weft fault, and means actuated by a warp fault for moving the dog into position to be actuated by the center fork weft stop mechanism that the loom may be stopped near front position on the occurrence of either a warp or weft fault.

40 5. In a loom, the combination of a warp stop mechanism and a weft stop mechanism, a shipper, a dog connected to the shipper and normally positioned to be actuated to stop the loom on the occurrence of a weft fault, and means actuated on the occurrence of a warp fault to move said dog into another position to stop the loom, that the loom may be brought to rest as the lay

moves towards front position on the occurrence of either a warp or weft fault.

6. In a loom, the combination of a warp stop mechanism and center fork weft stop mechanism including a dagger, a shipper, a dog connected to the shipper and normally positioned to be actuated by the dagger to stop the loom on the occurrence of a weft fault, and means actuated on the occurrence of a warp fault to move the dog into the path of the dagger for actuation thereby that the loom may be stopped with the lay in a frontward position on the occurrence of either a weft or a warp fault. 65

7. In a loom, the combination of a warp stop mechanism, a center fork weft stop mechanism including a dagger, a shipper, a pivotally mounted dog carrier connected to the shipper, a dog mounted on the dog carrier for engagement by the dagger on the occurrence of a weft fault, and means controlled by the warp stop mechanism to move the dog into the path of the dagger on the occurrence of a warp fault. 70

8. In a loom, the combination of a warp stop mechanism, a center fork weft stop mechanism including a dagger, a shipper, a pivotally mounted dog carrier connected to the shipper, a dog pivotally mounted on the dog carrier for engagement by the dagger on the occurrence of a weft fault, and means controlled by the warp stop mechanism to move the dog into the path of the dagger on the occurrence of a warp fault. 75

9. In a loom, the combination of a warp stop mechanism, a center fork weft stop mechanism mounted on the lay and including a dagger, a dog normally positioned for engagement by the dagger on failure of the weft, means actuated by the warp stop mechanism to move the dog into the path of the dagger on the occurrence of a warp fault, and means actuated by dagger movement of the dog to stop the loom in frontward position on the occurrence of either a warp or weft fault. 80

In testimony whereof, I have signed my name to this specification.

ARTHUR S. JOHNSON.
